CLAIM

The ornamental design for a bottle, as shown and described.

DESCRIPTION

FIG. 1 is a front, top and right perspective view of a first embodiment of a bottle showing our new design;

FIG. 2 is an elevational view of the front side thereof;

FIG. 3 an elevational view of the back side thereof;

FIG. 4 is an elevational view of the left side thereof;

FIG. 5 is an elevational view of the right side thereof;

FIG. 6 is a top plan view thereof;

FIG. 7 is a bottom plan view thereof;

FIG. 8 is a front, top and right perspective view of a second embodiment of a bottle showing our new design;

FIG. 9 is an elevational view of the front side thereof;

FIG. 10 is an elevational view of the back side thereof;

FIG. 11 is an elevational view of the left side thereof;

FIG. 12 is an elevational view of the right side thereof;

FIG. 13 is a top plan view thereof; and,

FIG. 14 is a bottom plan view thereof.

The broken lines in the drawings depict portions of the bottle that form no part of the claimed design.
